A. BRYNTESON

PISTON

Filed April 17, 1922

³ Inventor,
Alfred Brynteson
by F. S. Johnson
his Attorney.

UNITED STATES PATENT OFFICE.

ALFRED BRYNTESON, OF ST. PAUL, MINNESOTA.

PISTON.

Application filed April 17, 1922. Serial No. 554,259.

To all whom it may concern:

Be it known that I, ALFRED BRYNTESON, a citizen of the United States, residing at St. Paul, in the county of Ramsey and State of Minnesota, have invented certain new and useful Improvements in Pistons, of which the following is a specification.

My invention relates to piston constructions for internal combustion engines, as an article of manufacture, and has for its object to reduce the weight of the piston without sacrificing strength and durability.

A further object of the invention is to reduce the cost of production by providing features of construction whereby a piston may be built up of cast metal such as aluminum and ductile steel to form a composite compact unit which will be reinforced by the steel at important points in the structure.

It is a further object of the invention to provide a steel supporting base around which the aluminum parts are cast, which may be formed of ordinary steel tubing, suitably indented at points so as to form integral reinforcing members whereby the original strength of the tubing is retained.

Other objects of the invention will appear throughout the specification, the invention consisting in the novel construction, combination and arrangement of parts hereinafter to be described and claimed.

In the drawings forming part of this specification:

Fig. 1, is a side elevation of a piston shown partly in section embodying my invention.

Fig. 2 is a sectional view on line 2—2 of Fig. 1, a part thereof being broken away.

Fig. 3 is a sectional view on line 3—3 of Figs. 1 and 2.

Fig. 4 is a perspective view of the steel portion of the piston.

Fig. 5, is a side elevation of Fig. 4, partly broken away.

Fig. 6, is a sectional view on line 6—6 of Fig. 5.

Fig. 7, is a sectional view on line 7—7 of Fig. 4, showing the core therein,

Fig. 8 is a sectional view on line 8—8 of Fig. 4, and

Fig. 9, is a sectional view on line 9—9 of Fig. 1.

The invention comprises a soft steel shell portion 1, and a cast portion 2. The shell portion comprises a cylindrical or tubular

body portion 3, of relatively heavy tubing of uniform diameter, which forms the major portion of the shell; and a reduced recessed portion 4, concentric with said body portion and preferably welded or fused thereto. The body portion is formed with parallel ends 5 and 6, and with oppositely disposed indents 7, preferably spaced slightly from the end 6 thereof.

The indents are formed by cutting the wall of the tube transversely at 8 and 9, and bending inwardly the metal therebetween to form two opposite flat reinforcement bands or supports 10, preferably parallel to each other, the flat surfaces thereof being somewhat larger than the diameter of the usual wrist pin (not shown). The wrist pin journal or bore 11, extends radially at right angles to the longitudinal axis 75 of the piston, and extends through the reinforcing parts 10.

Positioned concentrically on the upper end 6 of the body portion is the reduced portion 4, the latter being formed with an upper and lower radial flange 12 and 13 respectively. The upper flange is somewhat smaller in diameter than the diameter of the body portion, while the shell or circumferential wall 13' between the two flanges, is somewhat smaller in diameter than the inner diameter of the body portion, whereby is formed the annular internal offset 14 and the outer annular recess 15. The shell 13' is cut away on opposite sides 90 at a point in vertical alinement with the indents 7 to form openings 16, and intermediate said openings, on opposite sides to form the openings 17. These openings extend between the flanges 13 and 12 and are 95 preferably vertically elongated. The flange 13 is perforated at intervals by the openings 17'. The recessed portion 14 is preferably spot welded to the body portion, though it may be secured thereto in any 100 other suitable manner.

While I have shown the shell formed of two parts welded together, it is to be understood that the shell may be constructed of a single piece of tubing and formed in a die 105 to reduce its upper end as shown in the drawings.

In Figure 1, 18 designates cast aluminum or other suitable material which is cast in the usual manner around the removable core 18', which latter fits the inner diameter 110 of the body portion and is formed with

- suitable cavities to mold the wrist pin bearing blocks 19. The cavities in the core are sufficiently large to cause the metal to embed the reinforcing bands 10, and, also, to 5 form a flat inner surface 19' parallel with the flat surface of the reinforcing members. As shown in Figs 1 and 2, these reinforcing members are entirely embedded including the lower edge thereof.
- 10 As best shown in Figure 4, the molten metal in the process of casting, will pass through the openings 20 above and below the reinforcing bands 10, to thereby fill the cavity 7. The metal will also flow 15 through the openings 16 and 17 and fill the annular recess 15 to bring the metal flush with the outer diameter of the body portion.

The mold is also formed to cast a top 20 wall 21 to form the top of the piston which latter will completely embed the flange 13 as shown in Figs. 7 and 8. For the purpose of reinforcing the top wall 21 the cross ribs 22 on the underside of the wall are 25 provided, said ribs registering with the openings 16 and 17 and extending down the inner side of the shell 13'.

As shown in Fig. 9, the ribs on the inner side of the shell form integral keys, whereby 30 the cast metal is interlockingly anchored to the shell. That part of the rib 22 which extends to the bearing blocks 19 merges with the latter to form the longitudinal ridge 23. Thus, the top wall of the piston is 35 firmly cast around the flanges 13 and 12, and anchored in the openings 16 and 17 of the shell. The piston may now be machined in the usual manner, the piston ring grooves 24 being wholly contained within 40 the annular recess 15 while the flange 13 forms a reinforcement for the cast metal above the first groove. The bore 11 for the wrist pin, as stated in the foregoing, extends through the reinforcement parts 10, 45 which latter provide stiffness and strength where it is most needed. By having the flange perforated as by the openings 17, the cast metal is firmly anchored in the flange, the latter serving as a reinforcement and a 50 stiffening member. By constructing the piston of ductile steel and cast metal as described, I am enabled to make the body portion of the piston much thinner than would be permitted if cast iron or aluminum 55 were solely used, as the steel is much stronger and tougher.

I have found that any unequal shrinkage which may occur between the steel at the top of the piston (where the heat is greatest) and the cast metal, will cause the relatively thin strip *b* of metal between the outer edge of the flange 13 and the openings 17' to fracture within the body of the cast metal, thereby preventing possible serious distortion if the flange was strong enough not to

yield. The strip *b* may be severed before casting if desired as indicated at *c* in Figure 6, when the openings 17' would constitute notches in the edge of the flange.

I claim:

1. A piston, comprising a tubular soft steel shell portion having indents in opposite sides thereof, said indents having openings in communication with the interior of said shell portion, and a cast metal 75 portion forming the top of the piston, said cast portion extending downwardly at opposite sides and filling said indents and extending through said openings and completely embedding the inner side of said 80 indents to thereby form wrist pin journal blocks.

2. A piston having a plurality of piston ring grooves comprising a tubular soft steel body portion open at the ends and an externally recessed portion secured concentrically to the top thereof, openings spaced at intervals in the circumferential wall of the recessed portion, and a cast metal portion 85 adapted to receive the piston ring grooves 90 forming the top wall of the piston and extending into said recess to completely fill the latter and extending interlockingly through and beyond said opening, the lower side of said recessed portion defining the 95 major circumferential portion of the lower internal border of said cast metal portion, for the purpose set forth.

3. A piston comprising a tubular soft steel shell portion open at the ends having 100 a relatively wide annular external recess adjacent the top thereof, oppositely disposed openings in the wall of said recess, a cast metal portion, forming the top wall of the 105 piston and extending into said annular recess to completely fill the latter and extending interlockingly inwardly through said openings and downwardly beyond said recess to form wrist pin journal blocks, and 110 opposite reinforcing members integral with 115 said body portion embedded one in each of said journal blocks.

4. A piston comprising a cylindrical soft steel shell portion open at the ends, the major portion of said shell being larger in 120 diameter than the minor portion thereof, a radial flange at the outer end of the minor portion, said flange somewhat smaller in diameter than the major portion of the shell, and a cast portion of the diameter of said major portion cast around said minor portion and across the top thereof so as to wholly embed said radial flange for the purpose set forth.

5. A piston, having piston ring grooves 125 adjacent the top thereof, said piston being formed of a cylindrical shell made of ductile steel extending beyond the piston ring grooves, said shell having a radial flange at its upper extremity formed with openings 130

occupying the major portion of the width of the flange for the purpose set forth.

6. A piston of the class described, comprising a cast top portion having peripheral piston ring grooves adjacent the top thereof, and a soft steel shell portion partially embedded in said cast portion to reinforce the

latter and extending downwardly therefrom to solely form the major portion of that part of the piston below the piston ring grooves. 10
In testimony whereof I affix my signature.

ALFRED BRYNTESON.
